UNITED STATES PATENT OFFICE.

HENRY W. WALTERS, OF JACKSONVILLE, FLORIDA, ASSIGNOR OF ONE-HALF TO
JOHN H. MACKEY, OF JACKSONVILLE, FLORIDA.

LIFE-SAVING APPARATUS.

1,380,026.

Specification of Letters Patent. Patented May 31, 1921.

Application filed January 26, 1921. Serial No. 439,999.

To all whom it may concern:

Be it known that I, HENRY W. WALTERS, a citizen of the United States, residing at Jacksonville, in the county of Duval and 5 State of Florida, have invented a new and useful Life-Saving Apparatus, of which the following is a specification.

This invention relates to life saving apparatus.

10 Objects of the invention are to provide apparatus which may be readily carried out to the drowning person or persons by a life guard, which is capable of effecting a rescue of a large number of people, which 15 will traverse waves without deflecting, and which is non-sinkable so that retrieving is made easy.

A further object is to provide an apparatus which may be carried out to deep 20 water by a swimmer and which may be drawn back to the shore again, if necessary, with the rescued persons clinging thereto, by a life guard or other person standing on the shore.

25 A still further object is to provide an apparatus which may be carried upon a reel so as to be ready in an emergency, without any adjustment, without liability of snarling or entangling the line.

30 Other objects will become apparent as the description is proceeded with.

The invention will be best understood from a consideration of the following detailed description taken in connection with 35 the accompanying drawing forming part of this specification, with the understanding, however, that the invention is not confined to any strict conformity with the showing in the drawing, but may be changed and modified 40 so long as such changes and modifications mark no material departure from the salient features of the invention as expressed in the appended claims.

In the drawing:

45 Figure 1 is a view showing the manner in which the apparatus is used to effect a rescue.

Fig. 2 is a cross section through the improved floating reel which forms part of the 50 invention.

Fig. 3 is a cross section of the same taken at right angles.

Fig. 4 is a longitudinal cross section through the improved buoy.

Fig. 5 is an elevation of the rod which 55 passes centrally through the buoy.

Fig. 6 is a cross section through the buoy on the line 6—6 of Fig. 4.

In the various figures of the drawing, the reference letter R designates the reel as an 60 entirety, the letter B represents the buoy, while L stands for the life-line. Each buoy B comprises a substantially cylindrical body 10 having ends 13 providing water-tight partitions. Two elongated conical end members 11 are joined, as at 12, to the opposite 65 ends of the cylindrical body 10, the whole forming a water-tight buoy having three compartments. Preferably the conical portions 11 have substantially the length of the 70 cylindrical portion 10. The provision of these elongated cones is necessary to permit the buoy to traverse waves. Were the 75 ends not brought to a point the buoy would offer a material impediment to the swimmer as he goes out into deep water to make the rescue.

Passing centrally through the buoy is a straight rod 14 having eyes 15 at each end. 80 Where the rod 14 encounters the partitions, apertures are provided and some water-tight means such as washers are used. Where the rod passes out of the buoy through the apices of the cones 11, a similar packing material may be used. 85

The cylindrical body member 10 has two or more circular straps 16 secured upon the outside thereof, said straps each having a pair of loops 17 raised above the surface of the cylinder so that a rope 18 may be run 90 through said loops and also through the eyes 15 of the rod. Preferably a single rope is used and passes through all of the loops 17 as well as the two eyes 15. This rope permits drowning persons to save 95 themselves by clutching, whereupon the supporting power of the buoy is made effective.

The reel R includes a handle or frame 22 straddling a pivotal rod 20 having a crank 23 at one end. Upon the rod 20 is secured a 100 hollow body 21 preferably cylindrical which forms the spindle of the reel. Circular flanges 24 are provided at the ends of the spindle 21, and the two flanges together with the member 21 provide a space upon 105 which the line L may be wound and stored. The body 21 is water-tight so that the reel has considerable buoyancy, and even when

- a portion of the line is wound thereon will float. The handle or frame 22 provides convenient means by which the reel may be hung upon a peg or other support.
- 5 In practice, the line is secured by snap hooks 19 to one or more of the buoys. Usually only one buoy is necessary, but where a large number of persons are bathing it is desirable to use a plurality of buoys.
- 10 since the distress of one person usually leads to the endangering of the lives of several others. As soon as the call for help is sent out, one of the life guards attaches the free end of the line to his suit and swims out to
- 15 the drowning person, while another life guard stands on the shore or in shallow water paying out the line. The buoys, because of their lightness, do not noticeably obstruct the swimming of the rescuer, and
- 20 because of their elongated pointed ends, traverse waves without being diverted from their course. After help has reached the drowning person, the buoy or buoys will support the body until the reel can be used
- 25 to wind up the line so as to bring the people into shallow water. Each buoy is capable of supporting a number of persons so that the rescuer as well as the rescued may cling thereto. Usually when the parties reach
- 30 shallow water the reel will be dropped by the guard who has been manipulating it so that he may assist his fellow workmen in getting the people to a spot where resuscitation or medical attention may be rendered.
- 35 If the reel did not float it would be difficult, especially in a pounding sea, to find it again. With the present apparatus, however, all the parts will stay on top of the water so that retrieving is easy.
- 40 Both the reels and the buoys are preferably made of copper, galvanized iron or other metal which will not oxidize. This is important since the apparatus is especially useful at salt water resorts. The snap
- 45 buckles 19, which are employed, permit rapid connection of any number of these buoys to each other and also allow quick detaching of the buoys if they are to be used alone. Furthermore the snap buckles can be caught
- 50 in the bathing suit of a guard so that swimming with the buoys is easy. The buoys and reel, being of light strong metal, float high upon the water but are nevertheless strong enough to withstand considerable abuse.
- 55 The bands 17 which pass around the cylindrical sections 10 of the buoys strengthen the interlocking joints 12.

What is claimed is:—

1. In a life saving buoy, a cylindrical body having pointed ends, a rope passing from 60 end to end on the outside of the buoy, and means at either end of the body for facilitating connection of a life line thereto.

2. In a life saving buoy, a cylindrical body having elongated conical ends, interior partitions separating the conical ends and the cylindrical body, an endless rope passing around the body from end to end and back again on the opposite side, and means on the outside of the body for holding the rope 70 in place and through which the rope is threaded.

3. In a life saving buoy, a cylindrical body having pointed ends, a rope passing from 75 end to end on the outside of the buoy, a rod passing centrally through the buoy and extending beyond both ends thereof, eyes on the two ends of the rod through which the rope passes, said eyes also facilitating connection of a life line to said buoy.

4. In a life saving buoy, a cylindrical body having elongated conical ends, loops provided on the outside of the cylindrical body, eyes at the apices of the conical ends, and a rope passing around the body through all of 85 said loops and eyes.

5. A life saving buoy comprising a substantially cylindrical body having closed ends, conical members joined to the opposite ends of said body, the closed ends of said 90 body providing water-tight partitions between the body and said members, and a rod passing longitudinally through said body and said members and having eyes at each end.

6. A life saving buoy comprising a body having pointed ends, eyes at each end of the body, straps encircling the body at spaced points and having eyes at each side thereof, and a continuous rope extending longitudinally along said body, passing loosely through all of said eyes, and arranged at opposite sides of said body.

7. In life saving apparatus, a floatable reel comprising a frame having an extended 105 portion providing a handle, a rod carried by the frame, a hollow body mounted on said rod having flanges at each end, and a crank provided on one end of the latter.

In testimony, that I claim the foregoing 110 as my own, I have hereto affixed my signature.

HENRY W. WALTERS.
